UNITED STATES PATENT OFFICE.

CONRAD DAUWALTER, OF DEEPWATER, MISSOURI.

BROOM.

1,049,459.

Specification of Letters Patent.

Patented Jan. 7, 1913.

Application filed May 2, 1912. Serial No. 694,773.

To all whom it may concern:

Be it known that I, CONRAD DAUWALTER, a citizen of the United States, residing at Deepwater, in the county of Henry and State of Missouri, have invented a new and useful Broom, of which the following is a specification.

This invention relates to brooms and brushes, and contemplates the production of a novel form of broom or brush, which will be substantial and inexpensive in construction, and which shall be convenient and efficient in use.

With the foregoing object in view, the present invention resides in the novel construction and combination of parts herein-after set forth and particularly claimed, it being understood that this device is susceptible of alterations or deviations in its details within the scope of the appended claim without departing from the spirit of the invention.

The invention has been illustrated in its preferred embodiment in the accompanying drawings, wherein similar reference characters have been employed to denote corresponding parts, and wherein,

Figure 1 is a side elevation of a broom constructed in accordance with the present invention, parts of the handle being broken away. Fig. 2 is a section on the line 2—2 of Fig. 1. Fig. 3 is a section taken on the line 3—3 of Fig. 2. Fig. 4 is an enlarged section taken on the line 4—4 of Fig. 1.

Referring specifically to the drawings, the present broom embodies a head consisting of two dished plates or sections 5, which have their edges converging at the upper end, as designated by the numeral 10, to form an apex 7 and having outwardly extended abutting flanges 6 along their edges, the lower ends of the sections and the apex being open. The lower ends of the plates or sections 5 are concaved as designated by the numeral 11. These plates or sections 5 may be constructed of any suitable metal, and may be of any preferred design or dimensions.

An independent filling or flat cluster of longitudinally extending broom corn, straw, or the like is arranged in each section 5, the butt ends of the broom corn, straw or the like, being disposed within the sections, and a longitudinally extending layer of stiff members, such as wire or the like, is arranged on each filling of broom corn and is

co-extensive therewith. The broom corn fillings or thick layers of vegetable fibers have been designated by the numeral 14, and the thin layers of stiff members or metallic fibers by the numeral 15, it being understood that the said parts may consist of any suitable materials for the purpose to which they are designed. When the sections 5 are assembled, there is formed a broom head having a central longitudinally extending layer of metallic fibers.

The flanges 6 are connected by rivets or other securing members 8 in order to clamp the sections together, and a row or series of rivets or other securing members 9 connect the lower ends of the sections and pass through the fillings of broom corn. The broom corn, or its equivalent, is retained within the sections by dipping the butt ends of the broom corn or straws in pitch, glue, or in any other adhesive material or solidifying agent, in order to provide a solidified mass within each section, or if desired, the pitch, mucilage, or the like, may be poured into the sections after the butt ends of the broom corn or straws have been placed therein, it being noted, however, that the solidifying agent or binder secures the butt ends of the fibers of each cluster *en masse* prior to their being assembled. Thus, when the sections are assembled and clamped together by means of the rivets 8, the broom corn or straws will be substantially held within the head.

The handle, which is of any preferred type, either wooden or of metal tubing, has its lower or inner end inserted into the open-apex 7 of the sections 5 and secured between the sections by means of the rivets or like securing members 13. The distance between the plates or sections 5 is approximately equal to that of the diameter of the handle 12 so that the handle fits snugly between the sections.

In use, the broom serves the ordinary functions, the stiff layers of wires or other stiff members 15 within the broom corn or straws serving to stiffen the broom and prolong the life thereof, it being understood that the said wires or stiff members 15 will wear away much slower than the broom corn or straws.

A broom or brush constructed in accordance with the present invention will be comparatively simple and inexpensive, and will be convenient and efficient in use, and it is

understood that this device is susceptible of alterations or deviations in its details within the scope of the appended claim in order to adapt the present invention for various purposes, and in order to permit the broom or brush to be constructed in various sizes and styles.

Having described the invention, what is claimed as new is:

- 10 A broom embodying two longitudinally extending layers of vegetable fibers, a layer

of similarly extending metallic fibers sandwiched therebetween, and means for securing the layers together.

In testimony that I claim the foregoing as 15 my own; I have hereto affixed my signature in the presence of two witnesses.

CONRAD DAUWALTER.

Witnesses:
